UNITED STATES PATENT OFFICE.

MARCUS ASH MYERS, OF GLOVERSVILLE, NEW YORK, ASSIGNOR TO MYERS' WOOLLY ANIMALS, INC., OF GLOVERSVILLE, NEW YORK, A CORPORATION OF NEW YORK.

PURSE.

Application filed May 10, 1927. Serial No. 190,181.

This invention relates to purses, and particularly to a novelty purse in the form of a toy animal.

The object of the invention is to provide a novel and attractive form of purse or the like, in which the purse proper is located or enclosed within the body of the animal, preferably being adapted to be opened and closed along the back of the animal, the article produced combining the useful functions of a purse or like receptacle with the attractive and striking appearance of a toy animal.

Another object of the invention is to provide certain improvements in the construction of the toy animal, particularly relating to the manner of stuffing the legs and other parts of the animal.

With these and other objects in view the invention consists in the novel features of construction and combinations and arrangements of parts as will be more fully herein-after described and pointed out in the claims.

The invention is illustrated in one form thereof in the accompanying drawings, in which:

Figure 1 is a side elevational view of the improved form of purse, certain parts being broken away in longitudinal section to more clearly show the construction and arrangement of the parts, and

Figure 2 is a cross sectional view taken on the line 2-2 of Figure 1.

The particular form of purse illustrated in the drawings is made up into the form of an animal by sewing or otherwise securing together a number of pieces of sheepskin or other suitable material to form the body portion 1 and legs 2 and tail 3 of the animal. It is preferred to employ in the making of the animal natural skin, for example, of the kind known as shearling, and to secure the pieces of skin together with the leather side innermost and the wooly part on the outside so that the toy animal approximates in appearance and touch to a real animal. In the drawings the leather part of the skin and the wooly part thereof are respectively indicated by the numerals 4 and 5.

The purse proper comprises a pocket or container 6 of flexible material, such as leather, arranged within the body of the animal, and preferably occupying practically the whole of the interior of this body por-

tion. The body portion is, as shown more particularly in Figure 2, provided with an opening 7 along the back of the animal, in extent substantially equal to the length of the pocket or purse 6, and the upper parts of the pocket or purse are suitably secured, as by stitching 8, to the edge portions of the skin adjacent said opening. The purse or pocket 6 is preferably left free within the body of the animal excepting for the attachment of the upper portions thereof at the opening 7.

The open side of the purse or pocket may be closed by any suitable form of closing means, the preferred form of closing means being that known commercially as the "hookless fastener". This fastener is indicated diagrammatically in the drawings at 9, the purse being opened by pulling the sliding member 10 in one direction, and being closed by pulling said sliding member in the opposite direction. Preferably a small piece or ring of skin 11 is attached to the ring 12 usually provided on such hookless fasteners.

It will be noted from the drawings that the major portion of the body of the animal is not provided with any stuffing or padding, as when the purse is in use, the articles contained within the pocket or container 6 will sufficiently fill out the body portion to give the same a proper appearance.

The leg and tail portions are, however, padded or stuffed, and an improved means for this purpose is employed. Each leg or tail portion has its own individual padding or stuffing element, which, as shown more particularly in connection with the tail 3 in Figure 1, comprises a bag or casing 13 of cloth or like flexible material, which is filled with the stuffing or padding material 14. The stuffed bag or casing so formed is of substantially the same size as the interior of the leg or tail portion so that when it is pushed or inserted therein it will properly fill out and pad said portion. The bag or pad may be positively secured within the leg or tail portion as by stitching at the outer end of said portion, and in the case of the leg portions the stitching may be so applied as to represent or indicate the feet of the animal.

The use of the pads or bags provides a simple and effective means for stuffing or

padding the leg and tail portions and prevents the stuffing from working out of said portions into the unstuffed body portion of the animal. It is preferred also to provide a wire member 15 extending lengthwise through each of the pads or bags 13, the wire being of such a nature that when bent the leg or tail portion will tend to remain in the bent position. Such wire may be secured by simply bending over the ends thereof as indicated.

The head portion 16 is preferably formed separately from the body portion and secured to the neck portion of said body portion as by stitching 17. The head portion is provided in the usual manner with eye members 18 and suitable stitching thereon to give it a proper appearance. It is also provided with side flaps 19 of skin to represent ears. The head is filled with a suitable stuffing or padding material 20 and to retain this material within the head, and in order to give the head and neck portions the proper shape and firmness a pad 21 is provided lying partly within the neck or body portion and partly within the head portion and suitably secured in place as by means of stitching. This pad is formed similarly to the pads 13 of the leg and tail portions, comprising a bag of cloth or like flexible material filled with the padding or stuffing material.

It will be seen that the article produced in accordance with the present invention may be carried as a toy animal, and at the same time has the useful function of a purse for carrying the usual articles. The article will usually be made of a size so that it can be carried under the arm, although this is not essential.

It will be understood that the invention is not restricted to the particular details of construction or materials specified herein, and that alterations or modifications may be made within the scope of the appended claims.

What I claim and desire to secure by Letters Patent is:

1. A hand bag comprising an animal shape made with a flexible outer covering, the extremities thereof, representing the body appendages of the animal, being distended to substantial rigidity, and the central portion representing the trunk of the animal body being hollow and flexible to permit bending of the same when pressed between the arm and body of the user, said central portion being provided with an article containing pocket, accessible through an opening in said covering.

2. A hand bag comprising an animal shape made with a flexible outer covering, the extremities thereof being distended to simulate the contours of the body appendages of the animal and the central portion

being hollow and pliant and provided with an article receiving pocket accessible through an opening in said outer covering.

3. A hand bag comprising an animal shape made with a flexible outer covering, the extremities thereof being distended to simulate the contours of the body appendages of the animal, and the central portion being hollow and pliant and provided with an article receiving pocket accessible through an opening in the outer covering upon the line corresponding to the backbone of the animal, and means operable by the user to close said opening.

4. A hand bag comprising an animal shape made with a flexible outer covering, the extremities thereof, representing the body appendages of the animal, being distended to substantial rigidity, and the central portion representing the trunk of the animal body being hollow and flexible to permit bending of the same when pressed between the arm and body of the user, said central portion being provided with an article containing pocket, accessible through an opening in said covering, and means operable by the user to close said opening.

5. A hand-bag comprising an animal shape in the form of a quadruped made of fur or fur-like material in hollow form and having fore legs and hind legs and head stuffed so as to be semi-solid and its mid-section or body portion unstuffed and pliant, the mid-section being provided with an article receiving pocket adapted to be partially filled with articles placed therein to give the mid-section a natural appearance, the animal-shape being formed with fore legs and hind legs extended from the body and sufficiently spaced apart to embrace the arm of the user and thus prevent accidental displacement when the article is confined at its mid-section between the arm and the body of the user.

6. A hand-bag comprising an animal shape in the form of a quadruped made of fur or fur-like material in hollow form and having fore legs and hind legs and head stuffed so as to be semi-solid and its mid-section or body portion unstuffed and pliant, the mid-section being provided with an article receiving pocket adapted to be partially filled with articles placed therein to give the mid-section a natural appearance, the animal-shape being formed with fore legs extending from the body so as to overlie the arm of the user and thus prevent accidental displacement when the article is confined at its mid-section between the arm and the body of the user.

7. A hand-bag comprising an animal shape in the form of a quadruped made of fur or fur-like material in hollow form and having fore legs and hind legs and head stuffed so as to be semi-solid and its mid-

section or body portion unstuffed and pliant, the mid-section being provided with a slit extending longitudinally thereof, the fore legs extending from the body so as to overlie the arm of the user and thus prevent accidental displacement when the article is confined at its mid-section between the arm and the body of the user, a lining in said

body constituting a pocket, the mouth of which is in said slit, said pocket being adapted to carry miscellaneous articles such as are usually carried in a purse or handbag, and means for closing said slit and hence said pocket to retain said articles therein.

In testimony whereof I affix my signature.
MARCUS ASH MYERS.
